(57) **CLAIM**

The ornamental design for a medical stopper, as shown and described.

DESCRIPTION

FIG. 1 is a front perspective view of a medical stopper, in accordance with an embodiment of the present design;

FIG. 2 is a bottom perspective view thereof;

FIG. 3 is a top plan view thereof;

FIG. 4 is a right side elevation view thereof, with the left side view being a mirror image thereof, the front view and the back view also being mirror images thereof;

FIG. 5 is a bottom view thereof; and,

FIG. 6 is a cross sectional view of FIG. 1.

The broken lines show portions of the medical stopper that form no part of the claimed design.
